United States Patent Office

Des. 211,233
Patented June 4, 1968

211,233

PANTY GIRDLE

Marguerite R. Williams, 500 Plattsville Road,
Trumbull, Conn. 06611

Filed May 8, 1967, Ser. No. 7,015

Term of patent 14 years

(Cl. D2—4)

FIG. 2

I claim:

The ornamental design for a panty girdle, substantially as shown.
